INCUBATOR EGG TRAY

Filed May 14, 1929

INVENTOR:

WILLIAM FINNEY HILL POT.

William T. Ritter, Esq.,
Attala Co.,
I. Thomas E. Saenger,
Attala Co.

UNITED STATES PATENT OFFICE

WILLIAM FINNEY HILLPOT, OF FRENCHTOWN, NEW JERSEY

INCUBATOR EGG TRAY

Application filed May 14, 1929. Serial No. 362,901.

My invention is particularly adapted for cooperation with incubator mechanism of the general character described and claimed in Letters Patent of the United States 1,489,597 granted to me April 8, 1924 and 1,545,425 granted to me July 7, 1925, wherein the means for supporting eggs include a vertical series of trays each supported by detachable connection with a plurality of vertically extending endless chain belts; whereby each tray is pivotally supported so that it may be tilted, to and from horizontal position, and inclined in either of two opposite directions to turn the eggs, with the object and effect of preventing the embryos from sticking to the shells; and each tray may be progressed vertically during the incubating period, from the place of introduction of the fresh eggs to the place of discharge of the hatched chicks. It is the object and effect of my invention to provide an incubator egg tray of more durable and sanitary construction than the ordinary wooden trays and having, in rigid connection therewith, suspension means affording respective points of suspension, in spaced relation, adapted to detachably fit in openings in respective flexible suspension connectors such as the chain belts aforesaid, and guiding means, also in rigid relation with the tray, arranged to rectilinearly limit the movement of the tray upon a loader guide rail such as is the subject matter of my copending application Serial No. 264,321 filed March 24, 1928 for Letters Patent of the United States for Improvement in incubator egg tray loaders. Such a loader includes a guide rail having a groove or recess extending longitudinally therein adapted to receive the guiding element fixed on the tray, and such loader also includes means for detachably engaging the flexible suspension connectors aforesaid, temporarily, so that the loader affords a support upon which such an egg tray may be slid between, and into detachable engagement with, said connectors, and such loading means also affords a temporary support upon which any tray may be withdrawn from engagement with said suspension means. My invention includes the various novel

features of construction and arrangement hereinafter more definitely specified.

In said drawings; Fig. I is a perspective view of a tray conveniently embodying my invention; the three flexible connectors being indicated in said figure by vertical dash lines.

Fig. II is an elevation of the left hand end of said tray, as indicated in Fig. I; but in cooperative connection with a loader.

Fig. III is an elevation of the opposite end of said tray and loader.

Fig. IV is a fragmentary, vertical, cross sectional view of the right hand end wall of said tray, as indicated in Fig. I, showing the loader engaging means in engagement with a fragment of said loader.

Fig. V is a fragmentary, diagrammatic, perspective view of a vertical series of egg trays supported by three vertical chains respectively suspended from chain wheels on three rotary shafts, being part of incubator mechanism claimed in my copending application Serial No. 264,320 filed March 24, 1928 for Letters Patent of the United States.

In said figures; each of the trays 1 has its bottom wall 2, opposite side walls 3 and 4, and opposite end walls 5 and 6 all formed of a single piece of reticulated wire fabric.

Each of said trays 1 has, rigidly connected therewith, at the upper edge thereof, a rigid rectangular frame 8. As indicated in Fig. IV; said frame 8 is conveniently formed of sheet metal bent to form pendent flanges 9 and 10 extending respectively inside and outside of said fabric side walls 3 etc., and rigidly connected therewith. I find it sufficient to pinch said flanges 9 and 10 together, with the fabric between them, at regions in spaced relation, for instance, as indicated at 12, 13, and 14 in Fig. I. However, said frame 8 may be otherwise rigidly connected with the tray, for instance, by spot welding or soldering operations, or by rivets.

Each of said trays 1 is provided with suspension means 16, 17, and 18, in spaced relation, adapted to engage the respective flexible suspension connectors 20, 21, and 22. Each of said suspension means 16, 17, and 18 is a metal hook in unitary connection with a substantially flat base plate, respectively 24,

25, and 26. Said plates are rigidly connected with said tray frame 8 by respective rivets 28, 29, and 30 in the respective vertically pendent position shown; so that all of the 5 parts of the tray above described are in rigid relation with each other.

As shown in Figs. I and II; said suspension means 16 and 17 are hooks which extend in respectively opposite directions at the regions thereof which engage the suspension means 20 and 21, but the points 32 and 33 of said hooks 16 and 17 point in the same direction, to wit, from the front end of the tray which is shown at the left hand side of Fig. 15 I, toward the rear end thereof; so that they may be simultaneously engaged in links or other openings in the flexible suspension connectors 20 and 21.

As shown in Figs. III and IV; the suspension means 18 is a hook, a portion of 20 which engages in a link or other opening of the flexible suspension connector 22, and extends in a direction different from, and in fact transverse to, the direction of the extension of said hooks 16 and 17, but the point of said hook 18 also points toward the rear of the tray so that the three hooks may be engaged with their respective suspension connectors by movement in the same general 30 direction, i. e., from front to rear.

As shown in Figs. III and IV; said plate 26 of the suspension means 18 has the guiding means 35 in unitary connection therewith, being a pendent projection which extends downwardly below said bottom wall 2 of the tray to a sufficient extent to adequately engage in the longitudinal groove or recess 36 of the guide rail 37 of the loader.

As indicated in Figs. I and II; said loader 40 rail 37 has the handle 38 at the outer end thereof and carries the cross bar 39 having hooks 40 and 41 at the opposite ends thereof in vertical alinement with the hook members 32 and 33 and pointing in the same direction, 45 so that said hooks 40 and 41 may be engaged in the vertical suspension connectors 20 and 21 in links or other openings beneath those to be engaged by said hook members 32 and 33. The opposite, inner, end of said loader 50 rail 37 has the hook 43 extending in the same direction as the other hook points aforesaid and adapted to be engaged in a link or other opening in the flexible suspension connector 22, beneath the opening in which the tray hook member 18 is adapted to be engaged.

The construction and arrangement above described are such that the three hooks of the loader may be respectively engaged with the flexible suspension connectors 20, 21, and 22 60 so that the loader is in position to temporarily support a tray, and the weight of a charge of eggs therein, while the tray is being slid in between the flexible suspension connectors 20 and 21 and into engagement 65 with those connectors and the connector 22.

After each tray 1 is thus engaged with said three flexible suspension connectors, the loader is withdrawn and inserted in position to thus temporarily support another tray during its movement into engagement with said connectors; so that vertical series of trays may be assembled in parallel relation in respective engagement with said connectors, as indicated in Fig. V. Of course, said loader may be similarly temporarily engaged with said connectors to facilitate the disengagement and removal of the successive trays from their position shown in Fig. V. In either operation of introduction or removal from the position shown in Fig. V, each tray is adapted to cooperate with the loader so as to facilitate such operation and enable a single operator to perform the same, whereas, without such cooperative means, two operators would be required to effect such operation while stationed at respectively front and rear ends of the trays.

In what is termed "custom hatching", it is necessary to identify each tray load of eggs with the name of the customer to whom the eggs belong and, for that purpose, I find it convenient to provide the tray with a card holder 45, conveniently formed of a sheet metal stamping rigidly connected with the frame 8 at its edges and affording a space between them for the insertion of a card 46 containing a name or other identifying mark.

However, I do not desire to limit myself to the precise details of construction, arrangement, or method of procedure herein set forth, as it is obvious that various modifications may be made therein without departing from the essential features of my invention, as defined in the appended claims.

I claim:

1. An incubator egg tray, including suspension means affording respective points of suspension, in spaced relation, adapted to detachably fit in openings in respective flexible suspension connectors; and guiding means on said tray arranged to limit to rectilinear reciprocation the movement of said tray upon a loader guide rail; whereby said tray is adapted to be temporarily supported and guided, upon a loader, to and from engagement with said suspension connectors.

2. An egg tray as in claim 1; including bottom and side walls formed of a single piece of reticulated wire fabric, and including a metal frame at its upper edge, connecting said suspension means and guiding means in rigid relation.

3. An egg tray as in claim 1; wherein the suspension means include a hook plate rigidly connected with the tray at one end thereof, and the guiding means is an integral part of that hook plate.

4. An egg tray as in claim 1; including a metal frame at its upper edge, connecting

5 said suspension means and guiding means in rigid relation.

5. An incubator egg tray having bottom and side walls formed of a single piece of reticulated wire fabric, and having a reinforcing frame at the upper edge of said walls including sheet metal forming flanges respectively pending inside and outside of said walls; tray suspension means on said 10 frame affording respective points of suspension, in spaced relation, adapted to detachably fit in openings in respective flexible suspension connectors; and respective fastening means for said suspension means; said fastening means extending thru said frame flanges and the reticulated fabric between them; whereby said walls, frame, and suspension means are rigidly connected.

15 In testimony whereof, I have hereunto 20 signed my name at Frenchtown, New Jersey, this 10th day of May, 1929.

WILLIAM FINNEY HILLPOT.
